Patented July 25. 1840.

July 25.

George W. & Henry Sizer, Springfield, Massachusetts,
Letters Patent (Design No. 71) dated 23rd July 1846
ante dated January 24th 1846)

The Schedule referred to in these Letters Patent making
part of the same.

To all whom it may concern:

Be it known that we

George W. Sizer, and Henry Sizer, of Springfield, in the County of Hampden,
and State of Massachusetts, have invented or produced a new and ornamental
stove, which we denominate Sizers Double Oven air light Cooking Stove,
and we do hereby declare the following to be a full and exact description
of the ornamental design of the same, reference being had to the accompanying
drawings in which it is represented, and which constitute a part of this speci-
fication. The nature of our invention consists in the combination of the ora-
mental designs, or carvings in the several doors and plates of our stove.
Fig. 1. of the accompanying drawings, is a perspective elevation of our stove.
The top plate is ornamented around its edge by a moulding—an enlarged
view of which is shown in fig. 2.

The front plate f. of our stove, is ornamented by a convoluted
fluted surface surmounted by a panel having the words Sizer & Co. Springfield,
Mass. cast upon the same; at the bottom of the front plate f. is a hearth g.
surrounded by a moulding of the same pattern as that surrounding the top plate
of the stove. The furnace door c. of our stove, is ornamented by a represen-
tation of fruit and foliage.

The front side plate of the stove, is ornamented on each

side of the furnace door, by a narrow vertical border of foliage; in the right hand upper projecting corner of the same, is also a representation of fruit and foliage. To the front oven door d, is concealed the furnace hearth and ash pit e, the cover of the ash pit has upon it the words - Sizer's Double Oven Air Tight Cooking Stove, patented 1844. - Fig. 2 is an elevation of the rear side of our stove, opposite the furnace door - a, is a panel, ornamented with a representation of fruit and foliage, b, is an oven door ornamented with the same devices as the panel above it - c, is a projection upon the upper corner of the rear plate ornamented with a cluster of fruit and foliage —

Having thus fully represented and described our ornamental Double Air Tight Cooking Stove, what we claim as original and desire to secure by Letters Patent is the general design & combination of the several ornamental parts thereof, as herein represented and set forth.
